UNITED STATES PATENT OFFICE.

JOHN D. PILTZ, OF TOLEDO, OHIO.

SHIP-PROTECTOR.

1,266,854.

Specification of Letters Patent. Patented May 21, 1918.

Application filed October 8, 1917. Serial No. 195,361.

To all whom it may concern:

Be it known that I, JOHN D. PILTZ, a citizen of Russia, residing at Toledo, in the county of Lucas and State of Ohio, 5 have invented certain new and useful Improvements in Ship-Protectors, of which the following is a specification.

The primary object of the invention is the provision of a protector arranged adjacent the water line of the ship, and provided with vertical adjusting means to compensate for the rising and lowering of the ship in the water under load conditions.

A further object of the invention is the provision of a buffer means adapted for preventing injury to ships from torpedoes traveling in the water adjacent the surface thereof, cushioning means being provided to stop the progress of the torpedo and prevent the same from exploding.

A still further object of this device is the provision of a ship protector that is readily carried in adjustable relation to the hull of a ship, and which neither impedes the progress of the ship nor interferes with the propelling and steering means thereof but assists in stabilizing the craft.

In the drawings forming a part of this application and in which like designating characters refer to corresponding parts through the several views,

Figure 1 is a side elevation of a ship provided with my device,

Fig. 2 is a top plan view thereof,

Fig. 3 is a vertical transverse sectional view through a portion of the same upon an enlarged scale and

Fig. 4 is a sectional view of a spring connection employed with the device.

My protector may be employed with any form of ship and is herein illustrated in connection with the ship 10, having a hull 11 provided with a deck 12, a cabin 13, pilot house 14, funnels 15 and wireless outfit 16.

The ship 10 is also provided with a rudder 17 and a propeller 18 at the stern 19 thereof while the buffer form of protector 20 surrounds the hull 11 and has the general outline of the hull.

The protector 20 has an inner layer 21 formed of a base plate or strip preferably of cork or other relatively light material and has a plurality of rollers 22 adjacent its inner face engaging the outer surface of the hull 11 for assisting in the vertical movement of the protector upon the hull. A

rubber plate 23 is carried by the base plate 21 for mounting a plurality of springs 24 which support a mattress 25 formed of layers of metal mesh or screens and constituting the outer layer or surface of the protector.

Flexible top and bottom strips 26 are connected between the base plate 21 and plate 23 and the outer mattress layer 25 which protect the springs 24 and yet allow the inward movement of the mattress 25 when hit by a projectile, such movement being cushioned by the springs 24.

Cables 27 are connected to the rings 28 upon the keel 29 of the hull 11 and are attached to the downwardly projecting rods 30 of resilient connectors 31 which also have upwardly extending rods 32 attached as at 33 to the lower outer edge of the protector 20. Of the connectors 31 each has its upper rod 32 provided with a head or piston 34 arranged within a cylinder 35 with a coil springs 36 connecting the piston 34, with the adjacent end of the lower rod 30. A removable upper cap 37 is provided for the cylinder 35 having a stuffing box 38 while a similar stuffing box 39 is arranged at the lower end of the cylinder. A plurality of cables 40 are attached to the upper outer edge of the protector 20 as at 41 and passed over pulleys 42 upon the deck 12 and thence over winding drums 42 carried by an operating shaft 43 centrally journaled upon the deck. By this arrangement, the protector 20 is normally positioned adjacent the water line where any oncoming torpedoes traveling adjacent the surface of the water will hit the mattress 25 which will withstand the shock of the contact, being cushioned by the springs 24 as well as the rubber plate 23 and the cork plate 21. When the cargo within the hull 11 lowers the ship into the water, the shaft 43 is turned by any desired means, for winding up the cables 40 and moving the protector 20 upwardly upon the hull 11. In this manner, the protector 20 may be readily adjusted for maintaining the same in proper relations to the water line of the hull 11, while the encircling cork plate 21 acts as a floating outrigger assisting in stabilizing the ship. Upon releasing the cables 40, the resilient connectors 41 act as take-ups for the cables 27 to lower the protector 20. The protector having a pointed bow portion 44 and having sides substantially conforming to the shape of the hull

11, the ship will be propelled through the water without being impeded by my protecting device, while the portion of the hull ordinarily exposed to the attack of torpedoes will be protected from injury.

5 What I claim as new is:—

A protector for hulls comprising an encircling float, rollers carried by the float adapted for engaging a hull upon which 10 the device is mounted, a mattress arranged outwardly of the float, resilient connections between the mattress and float, flexible top

and bottom members connecting the mattress and float and projectingly arranged adjacent the said springs, a drum mounted 15 upon the deck of the hull, cables attached to said drum and to said mattress, and separate cables having their lower ends attached to the hull adjacent the keel and their upper ends resiliently connected to the lower 20 edge of the mattress.

In testimony whereof I affix my signature.

JOHN D. PILTZ.
